Wm. Ford Burnam Design for Cigar Box Lid
Stone Design. Dated January 6, 1852. —

Ms. 433

No. 433

Sanford Burnam, of Waterford N.Y.
Letters Patent No. 433. Dated Jan'y 6. 1853.

The schedule referred to in these Letters Patent and making
part of the same. —

To all to whom these presents shall come:

Be it known
that I, Sanford Burnam of Waterford in the County of
Saratoga & state of New York, have invented or produced a new
design of stove which I call the "Parlour & Kitchen Gem" and I do
hereby declare that the following is a full & exact description
of the same, reference being had to the annexed drawings ma-
king a part of this specification in which,

Fig 1, is a

perspective view of the same, as a cook stove, and fig 2, is a perspective view of the parlor top. —

The ornamental design of my stove consists in the forming of gothic arches a & b forming panels or doors on which oak branches, leaves & acorns C, C, & arabesque figures d, d, are interspersed, the corners upon the lower section are ornamented with prominent arabesque clusters e, e, and the upper section with columns f, f; and arabesque figures are interspersed in recesses & prominent parts of the stove as represented. —

The base is ornamented with representations of oak branches, leaves & acorns as represented. —

When the stove is not used in cooking the ornamental top in fig 2, is placed upon the stove, which shall give it an entire appearance of a parlor stove, said top is ornamented in oak branches, leaves & acorns & other arabesque figures forming the centre as represented. —

This top may be made with openings throughout as represented in the shaded parts or made close as may be desired, the open top being designed to place upon the cook top, and a close top cast in the same design for an exclusively parlor stove as a permanent fixture.

Having thus described the design of my stove, what I claim & desire to secure by Letters Patent is the design & configuration of ornaments arranged & combined substantially the same as represented. —
